ROBERT M. GETCHELL, OF DAYTON, OHIO.

APPARATUS FOR DETERMINING THE MOMENT OF IGNITION IN INTERNAL-COMBUSTION ENGINES.

Application filed December 14, 1922. Serial No. 606,913.

This invention relates to an apparatus for determining the exact moment of ignition in the cylinder of an internal combustion engine.

The object in view is to provide simple, reliable and effective means for obtaining a record of the exact moment at which ignition takes place in the cycle of operation of an internal combustion engine. A further object in view is to provide means whereby the apparatus referred to may be adjusted to adapt the same to cylinders of different bores and piston strokes.

With the above and other objects in view the invention consists in the novel construction, combination and arrangement hereinbefore described, illustrated and claimed.

In the accompanying drawings—

Figure 1 is a side elevation of the improved apparatus.

Figure 2 is a section on the line A—A of Figure 1;

Figure 3 is an end elevation of the device;

Figure 4 is a diagrammatic view of an engine on which my invention is shown in use, the electrical connection therefor in the engine ignition circuit being also shown, and Figure 5 is a view of an ignition indicator card or record sheet produced by the use of my invention.

In carrying out the object of the present invention in the simplest and most effective form thereof, I employ an adapter 1 which closely resembles the shell of a spark plug, such as is now commonly employed in the ignition of internal combustion engines. The adapter 1 is intended to be screwed into the spark plug hole of the cylinder in the engine, taking the place of the ordinary spark plug for the time being, as shown in Figure 4.

Passing through the adapter 1 is an actuator 2 which consists of a lever, the same being mounted on a fulcrum pin 3 within the adapter 1 and having attached to the inner end thereof by means of a screw or other suitable pivot device 4 an adjustable extension or arm 5. By adjusting the extension 5 in relation to the actuator 2, the device may be adapted to engines having different bores and piston throws.

Attached to the adapter 1 by means of a threaded union 6, is a frame or bracket 7 having parallel guides 8 between which is

mounted a slide 9 adapted to reciprocate back and forth between the guides 8 at a right angle to the axis of the adapter 1 as shown in Figure 1. The slide 9 is connected to the actuator 2 by means of a pin 10, operating in a straight slot 10' in the bracket 7. The slide 9 carries at the opposite ends thereof cross guides 11, upon which is mounted a transversely movable record sheet holder 12 consisting of a rectangular plate which is adapted to carry on the surface thereof a record sheet 13 of metallic paper, that is, paper treated with copper iodide or ammonium nitrate solution or the like, said sheet being held on the plate 12 by means of spring clips 14 or any other suitable means. A typical record sheet is shown in Figure 5. The plate 12 is formed with a cam slot 15 which receives and cooperates with a pin 16 extending upwardly from the frame 7 thru a straight slot 16' in the slide 9. The slot 15 is curved oppositely at the ends thereof so that the pin 16 rides against the straight side thereof on the up stroke and on the other side thereof on the down stroke, shifting the plate sideways by cooperation with the curved ends of the slot 15. By the means described, the plate 12 and consequently the record sheet 13 has a compound movement or in other words it moves parallel with the guides 8 and also transversely with relation thereto. This is done so that the record will be inscribed with a continuous line having straight parallel side portions joined at the ends with a transverse curved portion for a purpose presently to appear. The slide 9 is moved in one direction by the actuator 2 and is returned by means of a spring 17, one end of which is attached to the actuator 2 and the other end to the frame at 18. A bracket 19 is mounted fixedly on the frame 7 and insulated therefrom by a strip 20 of insulating material. Mounted on the bracket 19 by means of a pivot 21 is a stylus carrying arm 22. Fastened to the arm 22 by means of a hollow screw 23 is a stylus 24 of steel or other metal which moves across the surface of the record sheet 13 for the purpose of making a record thereon for determining the exact moment of ignition in the internal combustion engine. The arm 22 is tensioned by means of a spring 25 adjustable by a screw 26. 27 designates a wire in the ignition circuit, which is nor-

mally connected with the spark plug of the cylinder being tested but which is now connected to a binding post 28 on the bracket 19 by means of a nut 29. The wire 27 has 5 connection with the ignition distributor shown at 30 in Figure 4 which is connected with the engine spark plugs 31 in the usual manner.

The operation of the apparatus is as follows: When the piston moves upward on the compression stroke toward the cylinder head, it comes in contact with the extension arm 5 of the actuator 2, causing said actuator to turn on its pivot 3. This causes the slide 9 to be moved in one direction against the tension of the return spring 17. At the moment of ignition, the current passes from the binding post 28 through the arm 22 and stylus 24 and through the metal paper record sheet 13, to the bracket 7 and adapter 1 where it is grounded in the frame of the engine. When the spark occurs, it jumps the gap in which the record sheet is interposed and punctures the sheet. The puncture is 25 very small and in the absence of the metallic salts thereon would be invisible except on holding the sheet to the light. The treatment of the paper makes it possible to read the record without removing it, due to the same being discolored at the point where the spark occurred and punctured the sheet. The record sheet is, of course, graduated or as shown in Figure 5 in suitable units of measurement, thereby to indicate the exact 30 moment of ignition occurring in the cylinder being tested. The line made by the stylus being straight up and down to correspond with the up and down movements of the piston, and joined by a transverse curved 35 portion where the piston is at the upper dead center position, the exact moment of ignition is readily determined since the puncture and discoloration will occur early or late on the curve if the ignition occurs before or 40 after the exact dead center position of the piston. In Figure 5 the sheet is shown as it is inscribed by the stylus and in this instance the puncture represented at 32 is off the dead center point designated by the numeral 33. 45 The extent is expressed in terms of the travel of the piston, and is represented by the distance between horizontal transverse lines thru the points 32 and 33, in the manner indicated. While the stylus has been described as composed of steel or other metal, other materials, such as carbon, for example, 50 may be used in place of metal.

What I claim is—

1. Apparatus for determining the moment 60 of ignition in the cylinder of an internal combustion engine, embodying recording means, and an actuator for operating said recording means in direct contact with the engine piston to be moved by the engine piston.

2. Apparatus for determining the moment of ignition in the cylinder of an internal combustion engine, embodying recording means, and an actuator for said recording means in direct contact with the engine piston to be moved by the engine piston, the recording means comprising a spark gap, a record sheet interposed in the spark gap, and the engine ignition circuit in which said spark gap and record sheet are included. 75

3. Apparatus for determining the moment of ignition in the cylinder of an internal combustion engine, embodying recording means, and an actuator for said recording means in direct contact with the engine piston to be moved by the engine piston, the recording means being included in and rendered effective by the engine ignition circuit. 80

4. Apparatus for determining the moment of ignition in the cylinder of an internal combustion engine, embodying recording means, an adapter insertable in the spark plug hole of the engine cylinder, and an actuator for the recording means mounted on said adapter, said recording means being 85 included in the engine ignition circuit. 90

5. Apparatus for determining the moment of ignition in the cylinder of an internal combustion engine, embodying recording means, and an actuator for said recording means adapted to be moved by the engine piston, the recording means being included in and rendered effective by the engine ignition circuit, said actuator being adjustable 95 for earlier or later cooperation with the engine piston. 100

6. Apparatus for determining the moment of ignition in the cylinder of an internal combustion engine, embodying recording means, and an actuator for said recording means in direct contact with the engine piston to be moved by the engine piston, the recording means being included in and rendered effective by the engine ignition circuit, and means for automatically resetting the 105 actuator and recording means in each cycle 110 of the engine.

7. In combination with an engine, means connected with the engine ignition circuit 115 replacing the spark plug in the spark plug opening of a cylinder of said engine having the electrical connection otherwise normally attached to said plug, for determining the moment of ignition in said cylinder.

8. In combination with an engine, means replacing a spark plug in a spark plug opening of a cylinder of said engine for determining the moment of ignition in said cylinder, said means being operated by the piston in its up and down movements so as to determine the moment of ignition in relation to the position of the piston at upper dead center. 120

9. In combination with an engine, means 125 for determining the moment of ignition in

- said engine comprising recording mechanism to be mounted in the spark plug opening replacing the usual spark plug of a cylinder of said engine included in and 5 rendered effective by the engine ignition circuit, said means being operated by the piston in its up and down movements so as to determine the moment of ignition in relation to the position of the piston at 10 upper dead center.
10. An apparatus of the character described comprising recording means, an adapter inserted in the spark plug opening of an engine cylinder, and an actuator 15 for said recording means mounted in said adapter extending into the engine cylinder for operation by the piston in said cylinder in its up and down movements.
11. An apparatus of the character de- 20 scribed comprising recording means, an adapter inserted in the spark plug opening of an engine cylinder, and an actuator for said recording means mounted in said adapter extending into the engine cylinder 25 for operation by the piston in said cylinder in its up and down movements, said actuator having an extension arm adjustably mounted on the inner end thereon to occupy positions farther up or down in the engine cylinder as respects the movements of the 30 piston.
12. A device for recording the operation of an engine cylinder connected in the electrical circuit of the engine and comprising 35 an actuating device entered in the engine cylinder for operation by the piston in its up and down movements.
13. In combination with an engine, a sup- 40 port to be mounted in the cylinder wall, a rocker arm pivoted therein having one end extending into the cylinder above the piston for operation thereby, an indicator card carried by said support, and a periodic electric spark operated in time relation with 45 the oscillation of said arm for making a record on said card.
14. In combination with an engine, a sup-
- port to be mounted in the cylinder wall, an actuating member carried by said support extending into the engine cylinder with its inner end above the piston to be operated thereby, an indicator card carried by said support, and a periodic electric spark operated in time relation with the moving of said member for making a record on said card.
15. In combination with an engine, a sup- 10 port to be mounted in the cylinder wall of said engine, an actuating member carried by said support extending into the engine cylinder with its inner end above the piston to be operated thereby, guides on said support, a slide reciprocated in said guides by said actuating member, a record on said slide, and a stationary stylus operating on said record.
16. In combination with an engine, a sup- 15 port to be mounted in the cylinder wall of said engine, an actuating member carried by said support extending into the engine cylinder with its inner end above the piston to be operated thereby, guides on said support, a slide reciprocated in said guides by said actuating member, a record on said slide, and a stationary stylus operating on said record and having a connection in the ignition circuit in insulated relation to the record, to cause a spark to pass thru said record at the moment of ignition.
17. In combination with an engine, a sup- 20 port to be mounted in the cylinder wall of said engine, an actuating member carried by said support extending into the engine cylinder with its inner end above the piston to be operated thereby, guides on said support, a slide reciprocated in said guides by said actuating member, a record on said slide, a stationary stylus operating on said record, and means for shifting said record laterally in its reciprocation.

In testimony whereof I affix my signature.
